CAN RUNWAY

Ronald E. J. Nordquist, Maplewood, N. J., assignor to American Can Company, New York, N. Y., a corporation of New Jersey

Application May 9, 1939, Serial No. 272,705

13 Claims. (Cl. 209—72)

The present invention relates to can runways and the like and has particular reference to ejecting deformed cans moving along a runway.

In the manufacture and subsequent handling of cans, they are usually transferred from one machine to another by way of runways. Frequently cans during such transfer become accidentally squeezed and pressed out-of-round. Occasionally a can is pressed so hard that the resulting deformation will prevent it from properly passing through a subsequent operation and will cause a jam in a machine to which it is delivered. The instant invention contemplates devices for detecting such cans while in the runway and for ejecting them before they can effect any damage to a machine or cause a tie-up in the can line.

An object therefore of the invention is the provision of a can runway mechanism which operates to eject moving deformed cans from a runway to a suitable place of deposit so that they will be prevented from entering a subsequent operation machine.

Another object is the provision of such a runway mechanism wherein the deformed cans are first detected and the detected cans are then ejected to a suitable place of deposit.

Another object is the provision of such a can detector and ejector mechanism wherein the cans roll in suspension along a magnet disposed over a bottomless runway section where the out-of-round cans are ejected and discharged after the detection of their deformed condition.

Numerous other objects and advantages of the invention will be apparent as it is better understood from the following description, which, taken in connection with the accompanying drawing, discloses a preferred embodiment thereof.

Referring to the drawing:

Figure 1 is a side elevation of a runway mechanism embodying the instant invention, the view also schematically indicating a machine to which the runway mechanism is connected, with parts broken away;

Figs. 2 and 3 are enlarged sectional views taken substantially along the lines 2—2 and 3—3 in Fig. 1; and

Fig. 4 is a wiring diagram of the electric apparatus used in the mechanism.

As a preferred embodiment of the invention the drawing illustrates an inclined can runway A the higher end of which preferably leads from some form of machine such for example, a can washing machine B for washing empty cans C prior to their being packed with food stuffs in a

subsequent operation machine. The opposite or lower end of the runway leads to such a subsequent operation machine. Out-of-round cans entering the runway A from the washer B are subjected to the action of detecting elements D which set in motion an electric time delay instrumentality associated with ejecting elements E. Such ejecting elements operate in proper time to throw out the deformed cans. The ejected cans fall into a discharge hopper F which directs them to any suitable place of deposit.

The inclined runway A includes a bottom or can supporting plate 11 (Fig. 1) along which the cans roll and a top channel plate or guide rail 12 having side flanges 13 for guiding the rolling cans along a predetermined path of travel. The can entrance end of the runway, i. e., that end which is connected to the washing machine B is formed with a built-up top wall section 15 (see also Figs. 2 and 3) which includes a pair of longitudinal and inclined permanent bar magnets 16 arranged on edge and held in spaced relation by a horizontal spacer plate 17. Narrow spacer blocks 18 are bolted to the outer surfaces of the magnets and can guide rails 19, which extend down below the magnets, are secured to the outer surfaces of the spacer block. There is no bottom in this section of the runway.

Hence as cans C enter the runway from the washing machine B they are attracted to and held against the inclined permanent bar magnets 16 as they roll in suspension along the magnets and down the incline. The body portion of the cans preferably engage the magnet bars as shown in Figs. 2 and 3 while the ends of the cans pass inside of the guide rails 19. The can bottom seam at one end of a can and the flange at the opposite end thus move along in clearance grooves 21 formed by the narrow spacer blocks 18 between the magnets and the guide rails.

The detector section D of the mechanism is located adjacent the can entrance end of the runway and in spaced relation to the bar magnets 16. This detector includes a narrow endless belt 26 located below the outer magnet adjacent the bottom or seamed end of a passing can C. The belt takes over a pair of spaced and grooved pulleys 26 mounted on short shafts 27 carried in bearings 28 formed in depending brackets 29 bolted to the side of the outer guide rail 19. The shafts are also carried in bearings 31 formed in horizontal legs 32 of depending brackets 33 bolted to the side of the inner guide rail 19.

One of the pulleys 26 serves as a driving pulley for moving the belt in time with a cam rolling

along the magnets. For this purpose there is provided a sprocket 35 on one of the pulley shafts 27 and this sprocket is driven by an endless chain 36 which takes over the sprocket and also operates with a driving sprocket 37 of the can washer B. The belt 25 helps to guide greatly out-of-round cans since these cans will necessarily wabble considerably as they roll along the magnets.

It will be understood that a deformed can is usually only out-of-round at the flanged or open end of the can since this end is the weakest part of the can. It is obvious that the end closure seamed onto the bottom of the can so strengthens that end that it will hold its shape and roll true while the out-of-round flanged end of the can will wabble along the magnet.

To detect this distortion of the out-of-round can mouth, a detector bar 41 is disposed adjacent the belt 25 and is located under the path of travel of the cans adjacent the open end. The ends of the detector bar are retained in slotted guide lugs 42 formed on the legs 32 of the brackets 33. The detector bar is yieldably mounted on a pair of spaced coiled compression springs 44 which surround vertically disposed stems 45 of a pair of normally open electric switches 46 carried on a connecting part 47 of the brackets 33. There is one of these switches at each end of the detector bar.

A normally round can rolls along the magnets 16 without touching the detector bar. Conversely an out-of-round can, as it wabbles along the magnets, somewhere along the length of the detector bar engages and depresses it. This closes one or both of the electric switches 46. Such an out-of-round can is shown in dotted lines in Fig. 2.

Closing of one or both of the switches 46 establishes certain electric circuits which will be hereinafter explained in connection with the wiring diagram in Fig. 4. The closing of these circuits sets in motion a time delay instrumentality associated with the ejector section E of the mechanism so that such a deformed and detected can will be ejected from the runway when it reaches the ejector elements.

The ejector elements E are disposed adjacent the detector elements D and include an elongated compressed air nozzle 51 (Figs. 1 and 3) disposed adjacent the path of travel of the cans along the magnets 16. The nozzle is located so that it will be effective only against out-of-round cans, being below the normally round cans passing by and also being inoperative at such a time.

Nozzle 51 is connected to a normally closed air valve 52 which is threaded onto one end of a pipe 54 leading to any suitable source of compressed air such as a supply tank or air compressor. The valve is provided with an operating stem 55 which is connected to a core 56 of an electric solenoid 57, the stem being normally held in valve closing position by a compression spring 58 disposed within the solenoid.

When the time delay instrumentality is brought into play by the detection of an out-of-round can, it energizes the solenoid 57 and thereby draws the core 56 into a centralized position. This movement of the core raises the valve stem 55 and thereby opens the valve 52. A blast of air from the supply pipe 54 is thereby permitted to issue from the nozzle 51 and when the out-of-round side of the detected can comes in line with the nozzle as indicated in dotted lines in Fig. 3, the air blast pries the can loose from the mag-

nets and discharges it from the runway, there being no bottom in this section of the runway.

The discharged can falls into the hopper F which is located below this section of the runway and is directed to any suitable place of deposit by a chute 61 which leads from the bottom of the hopper. In the chute there is located an arm 62 which is connected with a normally closed circuit breaking switch 63. The falling can trips this arm and momentarily opens the switch and thereby breaks the circuit and permits the various parts of the mechanism to return to normal.

Reference should now be had to the wiring diagram in Fig. 4. In this diagram one terminal of each of the normally open detector switches 46 is connected into a lead wire 101 which connects with a source of electric energy such as a generator, indicated by the numeral 102. The generator is also connected by a lead wire 103 to one end of the coil of a relay solenoid 104. The opposite end of the solenoid coil is connected by a wire 105 to the terminals of switches 46 opposite to terminals in the wire 101. Hence when one or both of the detector switches are momentarily closed a relay circuit is established which energizes the relay solenoid 104.

Energizing of the relay solenoid 104 closes a pair of normally open relay switches 107, 108. Closing of relay switch 107 establishes a holding circuit which includes the circuit breaking switch 63 and which maintains the relay solenoid energized so that the switches 107, 108 will remain closed when the detector switches 46 reopen. Establishment of this holding circuit permits electric energy from the generator 102 to flow along the lead wire 101, a connecting wire 111, switch 63, a connecting wire 112, relay switch 107, a wire 113, wire 105, relay solenoid 104, and returning to the generator along lead wire 103. Hence the relay solenoid remains energized.

The simultaneous closing of relay switch 108 establishes an air valve circuit which includes the air valve solenoid 57. This circuit diverts a portion of the energy flowing through the relay switch 107 and shunts it through the air valve solenoid 57 to energize it. This opens the valve as hereinbefore mentioned. The shunted energy passes from the wires 113, 105 along a wire 115 which connects with the switch 108 through the closed switch 107, a connecting wire 116, the coil winding of the air valve solenoid 57, a wire 117, and returns to the generator along the return lead wire 103.

When the circuit breaking switch 63 is momentarily opened by an ejected can falling through the chute 61 (Fig. 1), the holding circuit and the air valve circuit are both simultaneously broken and hence both solenoids, 104, 57 are deenergized. Deenergizing of the relay solenoid 104 opens the relay switches 107, 108 and this prevents immediate reestablishment of the circuits. Deenergizing of the air valve solenoid 57 permits the solenoid spring 58 (Fig. 3) to close the air valve 52 and hence cut off the blast of air. The circuits are thus made ready for their reestablishment when the next out-of-round can is detected.

It is thought that the invention and many of its attendant advantages will be understood from the foregoing description, and it will be apparent that various changes may be made in the form, construction and arrangement of the parts without departing from the spirit and scope of the invention or sacrificing all of its material advan-

tages, the form hereinbefore described being merely a preferred embodiment thereof.

I claim:

1. In a runway for the passage of cans therethrough and comprising a closed section and an open section, the combination of magnetic means for holding the cans in suspended position while the same are passing through the open section of the runway, detector elements disposed adjacent the open section of said runway for detecting cans which are deformed out of round, ejector elements disposed adjacent the path of travel of said deformed cans for ejecting the same through the open section of said runway, means responsive to and operable by said detector elements for actuating the ejector elements, and means for moving said cans past said detector elements.

2. In a runway for the passage of cans, the combination of a magnetic track along which the cans travel, and an air nozzle located outside the path of cylindrical cans passing along the track but within the path of a non-cylindrical portion of a passing defective can through which nozzle an air blast is projected to dislodge said defective can from the track and out of the runway.

3. In a runway for the passage of cans, the combination of means for suspending the cans while passing in said runway and while they are traversing a bottomless section of the runway, and an air nozzle located below the path of normal cylindrical cans passing over the bottomless section of said runway but within the path of a non-cylindrical portion of a passing abnormal can through which nozzle an air blast is projected to force said abnormal can away from its suspended means and out of said runway.

4. In a can testing runway having a closed section and an adjacent section open at its bottom, the combination of magnetic means for holding the cans in suspended position while the same are passing through the open section of the runway, the combination of detector elements disposed adjacent said open section for detecting cans which are deformed out of round, ejector elements located beneath the path of normal cans passing through the runway but adjacent the path of deformed cans passing therethrough, and electric time delay devices operable by said detector elements when so engaged for actuating said ejector elements to eject the detected deformed cans through the open bottom of said runway at a point remote from said detector elements.

5. In a can testing runway for round cans having a closed section and an adjacent section open at its bottom, the combination of magnetic means for holding the cans in suspended position while the same are passing through said open section of the runway, a detector bar disposed adjacent the path of travel of the cans along the runway and adapted to be engaged by out-of-round cans, stationary ejector elements disposed adjacent said runway and spaced from said detector bar for ejecting detected cans from the runway, and electric instrumentalities connecting the ejector elements with the detector bar for actuating said ejector elements to discharge from said runway an out-of-round can at the expiration of a time interval after said defective can is detected.

6. In a runway for testing cans for roundness and having a closed section and an adjacent detecting section open at its bottom, the combination of magnetic means for holding the cans in

suspended position while the same are passing through the open section of the runway, a yieldable detector bar disposed adjacent the path of travel of the cans along the runway and adapted to be engaged by out-of-round cans, an electric switch disposed adjacent each end of said detector bar, one or both of said switches being operated by the yielding of the detector bar when the latter is engaged by an out-of-round can section, stationary ejector elements disposed adjacent said runway for ejecting detected cans from the latter, and time delay electric instrumentalities connecting with and operable by said electric switches for actuating the ejector elements.

7. In a can testing runway having a closed section and an open section, the combination of magnetic means for holding the cans in suspended position while the same are passing through the open section of the runway, detector elements for detecting cans which are out-of-round, a stationary air ejector nozzle disposed adjacent the path of travel of the cans along the open section of said runway, a compressed air valve connecting with said nozzle, and means operable by said detector elements for actuating said air valve when an out-of-round can is detected and to thereby direct a blast of compressed air from the nozzle against the can to eject it through said open section of the runway.

8. In a runway for testing cans for roundness and having a closed section and an adjacent detecting section open at its bottom, the combination of magnetic means for holding the cans in suspended position while the same are passing through the open section of the runway, detector elements for detecting cans which are out of round, a stationary air ejector nozzle disposed adjacent the path of travel of the cans along the runway and spaced longitudinally therealong from said detector elements, a solenoid operated compressed air valve connecting with said nozzle, and time delay electric means operable by said detector elements and connecting with said solenoid operated valve for actuating the valve when an out-of-round can is detected and to thereby direct a blast of compressed air from the nozzle against the detected defective can to eject it from the runway at a point remote from said detector elements.

9. In a runway for testing round cans and including a closed section and a detecting section open at its bottom, the combination of magnetic means for holding the cans in suspended position while the same are passing through the open section of the runway, a movable detector bar disposed adjacent the path of travel of the cans along the runway and adapted to be engaged and traversed by out-of-round cans, stationary ejector elements disposed adjacent said runway for ejecting detected cans from the runway, electric instrumentalities connecting the ejector elements with the detector bar for actuating said ejector elements when a defective out-of-round can is detected to eject the same through the said open section of the runway, a chute disposed adjacent the ejector elements and said open runway section for directing an ejected can to a suitable place of deposit, and electric devices disposed in the chute and connecting with said electric instrumentalities for resetting the ejector elements for a subsequent ejecting operation.

10. In a can testing runway for round cans, the combination of a bottomless runway section, bar magnets in an inclined ceiling of said run-

way section for attracting cans thereto while permitting them to roll along the runway in suspension, detector elements constituting a portion of the bottom of said runway section for engaging and detecting out-of-round cans rolling along the magnets and over said detector elements, bodily stationary ejector elements also disposed adjacent the runway section for detaching detected cans from the magnets to thereby eject them from the runway, and means operable by said detector elements for admitting fluid under pressure to said ejector elements to impinge upon and eject from the runway said detected deformed cans.

11. In a can testing runway for round cans, the combination of a bottomless runway section, bar magnets in an inclined ceiling of said runway section for attracting cans thereto while permitting them to roll along the runway in suspension, means adjacent one end of the rolling cans for holding them against the magnets, detector elements constituting a portion of the bottom of said runway section for detecting out-of-round cans rolling along the magnets and over said detector elements, bodily stationary ejector elements also disposed adjacent the runway section, and means operable by said detector elements for admitting fluid under pressure to said ejector elements for detaching detected cans from the magnets to thereby eject them from the runway.

12. In a can testing runway for testing cans for roundness, the combination of a bottomless runway section, a pair of spaced and longitudinal bar magnets in an inclined ceiling of said runway section for attracting cans thereto while permitting them to roll along the runway in sus-

15 pension, guides for maintaining the rolling cans in alignment with the magnets, an endless belt arranged adjacent one of the magnets for holding one end of the rolling cans against the magnets, detector elements constituting a portion of the bottom of said runway section for detecting out-of-round cans rolling along the magnets and over said detector elements, bodily stationary ejector elements also disposed adjacent the runway section, and means operable by said detector elements for admitting fluid under pressure to said ejector elements for detaching detected cans from the magnets to thereby eject them from the runway.

13. In a can runway for testing sheet metal cans for roundness, the combination of a bottomless runway section, a pair of spaced and longitudinal bar magnets in an inclined ceiling of said runway section for attracting cans thereto while permitting them to roll along the runway in suspension, guides for maintaining the rolling cans in alignment with the magnets, an endless belt arranged adjacent one of the magnets for holding one end of the rolling cans against the magnets, actuating devices for propelling the belt in time with the cans rolling along the runway, detector elements constituting a portion of the bottom of said runway section for detecting out-of-round cans rolling along the magnets and over said detector elements, bodily stationary ejector elements also disposed adjacent the runway section, and means operable by said detector elements for admitting fluid under pressure to said ejector elements for detaching detected cans from the magnets and thereby eject them from the runway.

RONALD E. J. NORDQUIST.
